UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

BODY-ENCIRCLING BAND.

1,280,509.

specification of Letters Patent.

Patented Oct. 1, 1918.

Application filed October 12, 1916. Serial No. 125,201.

To all whom it may concern:

Be it known that I, CHESTER McNEIL, a citizen of the United States, residing at Chicago, in the county of Cook, State of Illinois, have invented certain new and useful Improvements in Body-Encircling Bands, of which the following is a description, reference being had to the accompanying drawing and to the figures of reference 10 marked thereon.

The invention relates to new and useful improvements in body encircling bands and more particularly to a waist-band for a garment.

15 An object of the invention is to provide a band of the above character having an elastic tape disposed in a fabric pocket with means for securing the fabric pocket and tacking the tape at certain portions thereof, which tacking means permits the tape to lie flat and straight to the end thereof.

A further object of the invention is to provide a band of the above character wherein the fabric pocket is secured to the body 25 portion of the garment by straight-away stitches and the elastic tape is tacked at certain portions by alternate stitches in a zig-zag line of stitches passing through the tape.

In the drawings which show by way of 30 illustration one embodiment of the invention:

Figure 1 is a perspective view of a portion of a waist-band having my improvement embodied therein.

35 Fig. 2 is an enlarged front view with parts broken away of one end of the waist-band.

Fig. 3 is a diagrammatic view showing the relation of the parts on the line a—a of Fig. 1.

40 Fig. 4 is a similar view on the line b—b of Fig. 1.

In carrying out the invention a fabric pocket is formed either from the fabric used in the making of the garment or by a 45 separate section of fabric stitched to the garment. An elastic tape is located within this fabric pocket. The fabric pocket is stitched by a line of stitches which passes along the side of the tape, but does not penetrate the tape. During this stitching of the 50 pocket the tape is stretched. Adjacent the ends of the tape or at the points where it is desired to tack the tape to the garment the straight-away line of stitches leads into and 55 forms a part of the zig-zag line of stitches

and this zigzag line of stitches is located so that alternate stitches pass through the tape and alternate stitches pass through the fabric parts adjacent the edge of the tape. When these tacking stitches are placed at the end 60 of the tape and the tape is released from the tension then the section of the fabric between the tacking will be gathered or fulled.

In the drawings I have shown the invention as embodied in a waist-band. The 65 waist is indicated at W. The lower edge of this band is turned up as at w and this edge is turned in at w' thus forming a hem fold and this hem fold serves as a pocket indicated at 1 for an elastic tape indicated at T 70 in the drawings. It will be understood that this pocket may be made by using a separate strip, if desired. The elastic tape extends from end to end of the pocket and its side edges throughout are parallel with the edge 75 of the pocket. The hem fold is stitched by a straight-away line of stitches 2 which pass through the folded edge w' of the hem fold and through the body portion of the waist. This straight-away line of stitches extends 80 along the side of the elastic tape, but does not penetrate the same.

The straight-away line of stitches leads into a zigzag line of stitches indicated at 3 in the drawings. This combined straight-away and zigzag line of stitches is made by a needle which is capable of being caused to vibrate laterally at the will of the operator without stopping the stitching mechanism so that the straight-away line 90 of stitches becomes a part of the zigzag line of stitches one leading into the other. There will, therefore, be no loose ends of thread between the straight-away line of stitches and the zigzag line of stitches. It will be 95 noted that alternate stitches in the zigzag line of stitches are in line with the straight-away line of stitches and pass through the body fabric and hem fold only, while the other alternate stitches of the zigzag line 100 of stitches are in a line at one side of the straight-away line of stitches and these alternate stitches pass through the elastic tape, thus firmly tacking the same. By this arrangement the tape may be tacked without 105 deflecting it in any way from its normal position, that is, the tape extends straight to the end thereof; neither is the line of stitches deflected, but continues straight to the end of the waistband, the needle moving 110

laterally to engage the tape at the points where it is tacked. This makes a very flat and neat, as well as durable, tacking for the tape. The tape is tacked by a minimum number of needle punctures, that is, the needle punctures in the tape are disposed the distance of two stitch lengths and this avoids cutting of the tape which might occur if every stitch in the straight line of stitches 10 passed through the tape. In the forming of the waist-band the needle is set so as to vibrate laterally, the zigzag line of stitches is formed and the end of the tape tacked; after which the operator without stopping the machine causes the needle to cease vibrating laterally and the straight-away line of 15 stitches will then be formed. The tape is stretched; while the waist-band is being stitched. When the other end of the waist-band is reached the operator, without stopping the stitching mechanism, causes the needle to vibrate laterally, thus producing the tacking stitches for the other end of the tape. When the stretched tape is released, 20 as above noted, the fabric between the ends of the tape will be gathered.

At each end of the band there is a fastening device which consists, as shown in the drawings, of a buttonhole indicated at 5 and a button indicated at 6, which is adapted to engage said buttonhole. In order that the band may be smooth and free from the elastic tape at the point where these fastening devices are attached I cause the needle 25 to vibrate laterally for tacking the tape at a distance back from the end of the band and then cause the needle to make straight-away stitches for a short distance at the end of the band. When the elastic tape is released 30 from tension it will be contracted and this will draw the tape within the pocket back from the end of the band, as clearly shown in the drawings.

While I have shown a combined straight-away line of stitches and zigzag line of stitches for securing the pocket and tacking the tape it will be understood that these lines of stitches may be modified, the essential feature being that the tape shall extend 45 straight to the end of the pocket and the lines of stitches throughout a greater portion of the extent of the band shall lie along the side of the tape securing the pocket and at certain points extend so as to extend to

one side of this line so as to pass through the 55 tape.

Having thus fully described my invention what I claim as new and desire to secure by Letters Patent is:—

1. The combination of a fabric having a 60 pocket extending across the same, a tape within the pocket extending longitudinally thereof and a combined straight-away and zigzag line of stitches for securing the pocket and tacking the tape at the ends thereof, the 65 straight-away line of stitches passing through the fabric adjacent the tape and alternate stitches in the zigzag line of stitches passing through the tape for tacking the same.

2. The combination of a fabric having a hem fold forming a pocket, an elastic tape extending longitudinally thereof, and a combined straight-away and zigzag line of 70 stitches for securing the pocket and tacking the tape, said straight-away line of stitches passing through the fabric at one side of the tape, alternate stitches in the zigzag line of stitches passing through the fabric in a line at one side of the tape, and alternate 75 stitches in the zigzag line of stitches passing through the fabric and the tape, said tape being stretched while the pocket is being stitched.

3. An encircling band including in combination a body fabric having a pocket extending across the same, fastening devices at the ends of the band, an elastic tape within the pocket and having its ends terminating between the fastening devices, said tape 80 having its edges throughout the entire length thereof parallel with the edge of the pocket, a continuous line of stitches for securing the pocket and tacking the tape adjacent its ends, said line of stitches passing 85 through the pocket at one side of the tape from a point adjacent one end of the tape to a point adjacent the other end thereof, alternate stitches in the continuous line at the ends of the tape passing through the tape 90 for tacking the ends thereof to the pocket.

In testimony whereof, I affix my signature, in the presence of two witnesses.

CHESTER McNEIL.
